Hunter, N.Y. 12442

Filed May 1, 1973, Ser. No. 356,160

Term of patent 14 years

Int. Cl. D16—06

U.S. Cl. D57—1 A

FIG. 1 is a perspective view of a spring temple for eyeglass frame showing my new design.

FIG. 2 is an enlarged fragmentary side elevational view thereof, the temple being fragmentarily shown for convenience of illustration.

FIGS. 3 and 4 are greatly enlarged cross-sectional views taken on lines 3—3 and 4—4 respectively of FIG. 2.

FIG. 5 is a fragmentary longitudinal sectional view taken on line 5—5 of FIG. 2.

FIG. 6 is an enlarged fragmentary perspective view of the spring temple, the temple being fragmentarily shown for convenience of illustration.

FIG. 7 is a side elevational view of the spring temple.

The frame front is fragmentarily shown in broken lines in FIGS. 1, 2 and 5 for illustrative purposes only.

I claim:

The ornamental design for a spring temple for an eyeglass frame, as shown and described.
